UNITED STATES PATENT OFFICE.

ROBERT M. DILLARD, OF GENEVA, NEBRASKA.

BUCKLE.

SPECIFICATION forming part of Letters Patent No. 331,378, dated December 1, 1885.

Application filed June 8, 1885. Serial No. 168,034. (No model.)

To all whom it may concern:

Be it known that I, ROBERT M. DILLARD, a citizen of the United States, residing at Geneva, in the county of Fillmore and State 5 of Nebraska, have invented certain new and useful Improvements in Buckles, of which the following is a specification, reference being had therein to the accompanying drawings.

The contrivance of this invention or improvement has for its object, while combining lightness and strength, to enable the securing of the straps so that they will emerge or extend from each end of the buckle about in alignment with each other; and to these ends 10 my invention consists of the detailed construction of the buckle, substantially as herein-after fully set forth and claimed. The tongue is brazed upon or cast with a bridge, which is also similarly connected to a plate of the 15 buckle-frame having at its ends cross-bars arranged in a plane below the free end of the tongue. The tongue is inclined away from the line of draft, to aid in preventing the accidental detachment of the strap or trace 20 therefrom.

In the accompanying drawings, Figure 1 is a side view, and Fig. 2 is a longitudinal sectional view, of my buckle as applied for use. Figs. 3 and 4 are a side view and a longitudinal 25 section, respectively, enlarged, of a modification of my buckle, also shown as applied for use, and Fig. 5 is a plan view of the same with the straps removed.

In the embodiment of my invention I employ a frame, A, of oblong rectangular form, with its sides composed of plates *a*, united at the ends, upon the upper edges, by cross-plates *a'*, cast therewith and arranged in a slightly-inclined position, the same sloping 30 outward, or toward the ends of the frame. The upper and lower edges of the side plates, *a*, are preferably convexed, the convexities of the lower edges extending the entire length thereof, while the convexities of the 35 upper edges terminate in concavities at each end of the frame. This constitutes a very light and strong frame. About centrally of the frame, and equidistantly of the cross plates or bars *a'*, is cast with the side plates, *a*, at their lower edges, a bottom plate, *b*, the same at its ends stopping sufficiently far from the cross plates or bars *a'* to permit of the

free or unobstructed passage of the harness straps or traces between said end plates or bars and the bottom plate. Upon the bottom 55 plate, *b*, is brazed, or with it may be cast a bridge or convexed piece, *c*, which may have only its ends resting upon the bottom plate, *b*; or it may be made so that its entire lower surface shall rest upon the bottom plate, being 60 in that instance made in a solid thickened piece, the sides of said bridge being firmly secured to the inner sides of the side plates, *a*, of the frame A. The strap *d*, which at one end is riveted to the bottom plate, *b*, so as to 65 rest upon said bridge or elevation *c*, it will be observed, is thus elevated at that point, as seen in Fig. 2, in order that when the second strap or a trace is passed through the frame A and over the strap *d*, as is common in fastening the free end of said strap or trace therein, the whole will be bulged or elevated so as to cause the upper or outer surface of the second strap or trace to project beyond or be 70 out of alignment with the end cross plates or 75 bars, *a'*, whereby as endwise pull or strain is exerted upon the second strap or trace the latter will be wedged and held tightly upon the tongue, next described.

B is the tongue, which is brazed upon or 80 cast with the bridge *c*, said tongue being disposed in a rearwardly-inclined position or in an opposite direction to the line, to more effectually prevent the accidental detachment from the trace or strap, through which hole in 85 strap or trace it passes.

In Fig. 4 it will be seen that a plate which answers to the bottom plate, *b*, of the preceding figures is connected to the side plates of the frame, intermediately of the upper and 90 lower edges of said plates, while the fixed strap is, in addition to being passed over said plate, also caused to underlap the latter, and the fastening-rivets are passed through and projected beyond both the upper and lower sides 95 of said intermediate plate, the projecting portions of said rivets passing through the underlapping portion of the strap, as well as through the upper or overlapping portion of said strap. By means of this construction of buckle the emerging portions of the straps are caused to extend about in alignment, whereby the draft or pull will be exerted in the plane of the length of the same,

thus uniformly distributing the strain or pull upon the straps and in the direction of the greatest resistance.

Having thus fully described my invention, 5 what I claim, and desire to secure by Letters Patent, is—

In a harness-buckle substantially such as herein described, a frame, A, having end bars, a' , and a plate, b , the latter having a bridge or

elevation provided with a rigid tongue inclined away from the line of draft, substantially as and for the purpose specified.

In testimony whereof I affix my signature in presence of two witnesses.

ROBERT M. DILLARD.
